ABSTRACT: A pipestem having a moisture vent leading downward from a moisture trap formed in the smoke passage therein, to a grooved portion on the exterior of the stem. An absorbent member is applied externally to the stem over the outlet of the moisture vent within the groove.

PIPESTEM

BACKGROUND OF THE INVENTION

Pipe stems as heretofore constructed have been difficult to keep dry. Some of them have been built with internal means for trapping or absorbing moisture. Such internal means often require the pipe stem to be separated from the bowl and a pipe cleaner to be inserted into the stem to remove the accumulated moisture. Even where internal moisture collecting devices have been employed, the smoke passage will become laden with moisture and sludge if for no other reason than that the moisture collecting device is located inside the pipe stem.

Examples of such prior art constructions may be found in the following U.S. Pats. Nos.:

Elam 921,527
Kostamo 2,163,432
Torres 2,100,093

SUMMARY OF THE INVENTION

It is a primary object of this invention to provide an improved pipe stem having means for dealing with the problems of moisture and sludge in order to maintain the smoke passage substantially dry at all times.

Another object of this invention is to provide a pipe stem having means for collecting saliva from the pipe stem, such collecting means being located externally rather than internally of the pipe stem.

Another object is to provide a pipe having a moisture vent leading downward from the smoke passage and means applied externally to the pipe stem over the outlet of the vent for collecting moisture.

Another object is to provide a pipe in which the means applied over the pipe stem to collect moisture preferably comprises a nonperforated flexible strip wrapped around the pipe stem and preferably having a moisture absorbing pad over the moisture vent outlet.

Another object is to provide the smoke passage in the pipe stem with a well or trap in the smoke passage over the moisture vent preferably separated from the tobacco bowl by a barrier wall to prevent saliva in the pipe stem from entering the tobacco bowl and thus forming sludge.

Other objects and features of this invention will become apparent as the description proceeds, especially when taken in conjunction with the accompanying drawing, wherein:

FIG. 1 is a longitudinal sectional view of a pipe constructed in accordance with my invention.

FIG. 2 is a sectional view taken on the line 2-2 in FIG. 1.

FIG. 3 is a detail plan view of a strip having an absorbent pad which is wrapped around the stem of the pipe.

FIG. 4 is an enlarged sectional view of a portion of FIG. 1.

FIG. 5 shows a modified pipe stem in longitudinal section.

Referring now more particularly to the drawing and especially to FIG. 1, the pipe there shown is generally designated by the reference numeral 10 and comprises a tobacco bowl 12 and a pipe stem 14. The bowl 12 has a tubular shank 16 extending laterally outwardly from the lower portion of the bowl. The passage 18 in the shank communicates with the bottom of the tobacco bowl.

The stem is a straight stem having a mouthpiece 20 at one end and having its opposite end reduced in diameter as indicated at 22 to fit removably within the end 24 of the shank. The smoke passage 26 in the pipe stem extends from end to end of the stem and communicates with the passage 18 in the shank.

The smoke passage 26 enlarges gradually from the mouthpiece toward the bowl 12 because of the downward incline of the bottom wall of the passage, forming a cavity or well or trap 28. Saliva which may be present in the pipe stem

will tend to run toward or settle in the trap portion of the smoke passage. A moisture vent 30 in the pipe stem extends downwardly from the trap at an inclination toward the bowl end of the pipe and has an outlet opening through the exterior wall of the stem. The end of the moisture trap 28 adjacent the shank 18 is defined by a barrier wall 32 which extends downwardly at an inclination toward the bowl end of the pipe. Preferably this wall extends in continuation of the moisture vent 30 and at substantially the same angle as the moisture vent so as to direct moisture in the trap downwardly through the vent.

The external surface of the pipe stem has an annular groove 34. The moisture vent 30 has its outlet opening into this groove.

15 A flexible preferably nonperforated strip 36 of tape or the like is wrapped around the stem of the pipe in the groove and preferably has a moisture absorbing pad 38 secured to its inner surface and covering the outlet of the moisture vent 30 so as to collect moisture. This strip may be similar to an ordinary adhesive bandage of the type used to cover a cut on the finger, in which the opposite ends of the strip have adhesive applied to the inner surfaces. The strip thus is preferably held on by its own adhesive similar to a postage stamp and may be readily peeled away and disposed of periodically and replaced by another clean strip having a dry moisture absorbing pad.

20 The strip 36 is applied externally to the pipe and is therefore very readily removed and replaced. The pipe does not have to be taken apart by removing the stem from the bowl. Since the moisture pad is on the outside of the stem the atmosphere within the smoke passage may be substantially kept dry at all times. The trap 28 causes saliva to move in a direction toward the vent 30 so that it will not accumulate within the smoke passage but will be quickly discharged to the exterior of the stem. The barrier wall 32 will prevent moisture which is moving toward the vent 30 from entering the tobacco bowl and thereby become foul and rancid and sludge forming. It may be necessary however to clean the accumulation of nicotine, tars, carbon, etc. from the smoke passage in the bowl shank along with any natural moisture that is in the tobacco. It will also be desirable to keep the stem hygienically sweet by using a commercial formula pipe sweetener.

30 FIG. 5 illustrates a modification of the pipe stem in which similar parts are designated by the same reference numerals. The principal difference in the FIG. 5 construction is that the pipe stem is of the bent or down-curved type rather than straight as in FIG. 1. Otherwise, the construction in FIG. 5 is like that of FIG. 1.

I claim:

1. A smoker's pipe having a tobacco bowl generally vertical, 50 a stem extending laterally from the lower portion of said bowl, said stem having a smoke passage communicating with said bowl, a moisture vent in said stem extending downward from said smoke passage and having an outlet through the exterior surface of said stem, means applied to the exterior surface of said stem over said outlet to collect moisture from said vent means providing a moisture trap at and over said vent and a barrier wall between said trap and said bowl to prevent saliva from reaching said bowl.

2. The pipe defined in claim 1, wherein said means comprises a moisture absorbent pad covering said outlet.

3. The pipe defined in claim 1, wherein said means comprises a flexible strip surrounding said stem.

4. The pipe defined in claim 1, wherein said means comprises a flexible strip surrounding said stem and having a moisture absorbent pad covering said outlet.

5. The pipe defined in claim 4, wherein said exterior surface of said stem has an annular groove through which said outlet opens, and said strip is disposed in said groove.
